FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof;

FIG. 14 is a fourteenth image thereof;

FIG. 15 is a fifteenth image thereof;

FIG. 16 is a sixteenth image thereof;

FIG. 17 is a seventeenth image thereof;

FIG. 18 is an eighteenth image thereof;

FIG. 19 is a nineteenth image thereof;

FIG. 20 is a twentieth image thereof;

(Continued)

FIG. 21 is a twenty-first image thereof;
 FIG. 22 is a twenty-second image thereof;
 FIG. 23 is a another embodiment of a display screen or portion thereof with animated graphical user interface showing a first image of the claimed design;
 FIG. 24 is a second image thereof;
 FIG. 25 is a third image thereof;
 FIG. 26 is a fourth image thereof;
 FIG. 27 is a fifth image thereof;
 FIG. 28 is a sixth image thereof;
 FIG. 29 is a seventh image thereof;
 FIG. 30 is an eighth image thereof;
 FIG. 31 is a ninth image thereof;
 FIG. 32 is a tenth image thereof;
 FIG. 33 is an eleventh image thereof;
